Fig. 1a.

Fig. 14.

Fig. 13.

A hand-drawn map of a building layout. The layout consists of several rooms and a central corridor. Key features include:

- Room 39:** Located at the top center, connected to a corridor.
- Room 41:** Located at the top left, connected to a corridor.
- Room 42:** Located in the center, connected to a corridor.
- Room 43:** Located on the left side, connected to a corridor.
- Room 44:** Located at the bottom left, connected to a corridor.
- Room 45:** Located at the bottom center, connected to a corridor.
- Room 46:** Located at the bottom right, connected to a corridor.

The map uses dashed lines to represent walls and solid lines for doorways or openings between rooms.

UNITED STATES PATENT OFFICE

DANIEL NACHTIGAL, OF HIBBING, MINNESOTA

COLLAR BUTTON

Application filed May 31, 1929. Serial No. 367,545.

My present invention has reference to a new and novel button or fastener for attaching the back of a collar to the neck band of a shirt, the primary object being the provision 5 of an article for this purpose which may easily, conveniently and quickly be attached to both the neckband and the collar to hold these members fastened together without any liability of accidental release and which may 10 be likewise as conveniently and readily detached from engaging position.

A further object is the provision of a collar button or fastener that shall have no projecting parts that will wear out the shirt band and collar, which will securely lock the collar to the shirt and which while simple in construction is strong and durable.

A still further object is the novel manner in which the elements constituting the improvement are constructed in order to add to the strength, durability and the successful employment thereof when in actual use.

To the attainment of the above broadly stated objects and many other objects which will present themselves as the nature of the invention is better understood, the improvement also resides in certain other novel features of construction, combination and operative association of parts, satisfactory embodiments of which are disclosed by the accompanying drawings.

In the drawings:

Figure 1 is a sectional view through the neckband of a shirt and a collar which are connected in accordance with this invention.

Figure 2 is a face view of the improvement.

Figure 3 is a sectional view on the line 3-3 of Figure 2.

40 Figure 4 is a transverse sectional view on the line 4-4 of Figure 3.

Figure 5 is a sectional view substantially similar to Figure 3 but showing the slidable latch member moved to permit of the outward 45 swinging of the front plate away from the back plate.

Figure 6 is an elevation showing the button in open position.

Figure 7 is a plan view of the blank from which the front plate is formed.

Figure 8 is a similar view of the blank from which the back plate is formed.

Figure 9 is a face view of the slidable latch.

Figure 10 is a front elevation to illustrate another form of the improvement.

Figure 11 is a sectional view approximately on the line 11-11 of Figure 10.

Figure 12 is a view of the button in open position.

Figure 13 is a sectional view approximately on the line 13-13 of Figure 11.

Figure 14 is a view of a blank from which the button is formed.

Figure 15 is a view of the blanks from which the latch engaging lip is formed.

Figure 16 is a view of the blank from which the slideable latch is formed.

My improved back collar button may be constructed of any desired material sufficiently light and thin to accomplish its purpose. In both of the forms illustrated both of the plates constituting the improvement are of a substantially rectangular formation and preferably in both forms the plates have a tendency to swing toward each other, this being especially true with respect to the construction disclosed in Figures 10 to 16 of the drawings. Referring now to the drawings in detail and to Figures 1 to 9 in particular, reference is especially to be had to the blanks disclosed in Figures 7, 8 and 9 thereof. The plate or

member of the button which is employed between the folds of the neck band will for distinction be referred to as the back plate and

the plate which is disposed between the folds of the collar will for distinction be referred to as the front plate. A blank from which

the front plate is formed is illustrated in Figure 7 of the drawings. The front plate is of a substantially rectangular form, having

a substantially rectangular formation and includes a face or body 1 that is approximately centrally formed with a substantially rec-

4) centrally formed with a substantially rectangular notch 2. The plate at an equidistance from the sides of the notch 2 is provided

with inner score lines 3 and with outer score lines 4 which are disposed in close relation to each other. From the score lines 4 the plate is formed with extensions 5. The upper edge of the plate 1, in a line with the upper

edges of the extensions 5, is provided with a comparatively small extension 6, the same being of a width equaling the distance between the score lines 3 and 4 and this extension is divided from the plate 1 by a transverse score line 7. The side extensions 5 have the portions thereof whose ends terminate in a line with the score line 4 widened and the said extensions 5 in a line with the upper wall provided by the notch 2 is cut inwardly and from thence is reduced. These reduced portions, indicated for distinction by the numerals 8, merge into extensions that project beyond the lower edge of the plate 1. The blank is first folded upon the score lines 3 and 7 so that the extension 6 provides the top of the front member of the button and the parts 9 between the fold lines 3 and 4 provide the sides of the button. The extensions 5 and 20 are folded against the rear of the plate 1 and thus afford the back of the front member of the button. When the extensions are thus folded the extensions 5 and their reduced portions 8 are folded on the score lines 4 and provide the back of the front member of the button. Of course, a suitable die or like machinery is provided for folding the blank and when folded the front of the button provides a substantially rectangular hollow member. 30 Also when folded the outer edges of the extensions 5 contact with each other but the parts 8 of the said extensions are slightly spaced away from each other. Also preferably the upper portions of these parts 8, at 35 their juncture with the extensions 5 are notched, as at 11. The projecting portions of the extensions 8 are now rounded upon themselves to provide what I will term barrels 12.

40 A substantially rectangular plate of a size to be freely received between the sides 9 of the hollow front button member but of a materially less length than that of the said front is inserted through the open bottom of the front. This plate is indicated by the numeral 45 13 and is constructed of a blank of metal as disclosed by Figure 9 of the drawings and provides the slideable latch member of the improvement. The latch member is centrally formed with a rectangular notch or opening 14 and has on its lower edge an extension which is bent right angularly to provide the same with a finger piece 15 which is freely guided between the confronting edges of the 50 reduced portions 8 of the back members 5 of the said front. The slideable latch is held in position in a manner which will be presently described. The blank for the back plate of the improvement disclosed by Figure 8 of the drawings is also of a substantially rectangular formation. This plate is of a 60 length or height corresponding to that of the front. The back plate, indicated by the numeral 16, is provided with spaced longitudinal score lines 17 and the distance between 65

these score lines equals the width of the front button member. The extensions 18, which project beyond the score lines 17 are designed to be folded over the rear of the back button member and thereby materially strengthen 70 and reinforce the same. Before the extensions 18 are folded the plate 16 is provided with both lateral and longitudinal slits and the metal bounded by these slits is bent outwardly to form the same with a lip 19 provided with a reduced extension 20 whose end is bent upwardly to form the back plate with a hooked lip. The plate 16, in a line with the score lines 17 has projecting beyond the lower edges of the extensions 18 a substantially T-shaped portion, the inner and widened end of which is indicated for distinction by the numeral 21 and the outer and reduced portion of which is indicated by the numeral 22. There is a score line 23 between the part 21 and the plate 16 and the said part 21 is bent right angularly on the score line 23 and the reduced extension thereof is rounded upon itself to provide a barrel designed to be received between the barrels formed by the extensions 12 of the front. A pindle 24 passes through these alining barrels. The extension 21 holds the slideable latch 13 in the pocket provided therefor by the front button member. The angle portion or flange 21 provides a base between the front and back button sections, and the hooked lip of the back section is adapted to move through the notch or opening 2 in the front button member when the button members are swung toward each other and the sliding latch may be moved by pressure exerted upon the finger piece 15 to bring the hooked end 20 of the lip 19 to within the notch or opening 14 in the said latch and thus easily and effectively lock the button members associated.

By reference to Figure 1 it will be seen that the hooked lip of the back member is inserted through the button hole openings in the collar band 25 of a shirt through the collar button opening of a fold collar 26. There may be a slight frictional engagement between the slideable latch and the pocket provided in the front button member to hold the said latch from free movement, but the weight of the latch will be also found sufficient to prevent the same from accidental movement after the same is brought into locking engagement with the hooked end 20 of the lip 19.

In Figures 10 to 16 of the drawings I have illustrated a rear or back collar button in which both the front and back members of the said button are formed from a single sheet or strip of suitable material that has a desired resiliency. By reference to Figure 14 of the drawings it will be seen that this form of button includes a body plate of rectangular formation. The plate is somewhat elongated, as both the back and front are formed therefrom. The end or portion of the plate

which affords the back of the button is indicated by the character 27 and the end or portion of the plate which affords the front of the button is indicated by the character 28. 5 The part 27 is formed with side extensions 29, respectively. The plate 27 is provided with longitudinal spaced score lines 30 and 31, the score lines 30 being in a line with the edges of the plate proper and the score lines 31 being arranged in the extensions 29. The 10 extensions 29 outward of the score lines 31 and approximately in a line with the center thereof are notched, as at 32, from the edges thereof. The back element of the button is first bent upon the score lines 30 and from 15 thence upon the score lines 31. The portions 33 between the score lines 30 and 31 afford the sides of the back of the button, while the portions of the extensions 29 outward of the score lines 30, after being bent inwardly upon 20 the said score lines provide the back of the part 27 of the button. Before these portions are bent there is arranged between the side and the back of the part 27 of the button plates having lips which project through the 25 notches 30. As disclosed by Figure 15 of the drawings two lip carrying members or plates of a similar shape and design are employed. Each of these members includes a body portion 34 having on one of its edges a reduced extension 35 that merges in a further reduced extension 36, the latter being formed with a notch 37, and a transverse score line 38 between each plate 34 and the extension 35 30 thereon and the body plates 34 are bent in opposite directions upon the score line so that the extensions 35 and 36 will project therefrom at a right angle therethrough. The angle portions or extensions 35 and 36 35 are arranged inlapping relation and are then inserted in the pocket provided in the part 27 of the button in a manner as heretofore described, the extensions 35 projecting through the notches 32.

40 The front plate 28 is centrally provided with an inverted T-shaped slot or opening, the longitudinal wider and longer passage of which is indicated by the numeral 39 and the narrower transverse passage by the numeral 40. The part 28 is provided with side extensions 41 divided from the part 28 proper by an inner score line 42 arranged in a plane with the score line 30 and with an outer score line 43 arranged in a plane with the score line 44. The extensions 41 are of a greater width than the extensions 27 and the same are centrally and transversely notched, as at 45, in a line with the transverse passage 40 of the inverted T-shaped slot and likewise in a line 50 with the notches 44. The part 28 has its end provided with a reduced extension 46 divided from the part 28 proper by a transverse score line 47, the said score line being in a plane with the outer ends of the extensions 41 and 55 being of a length approximately equaling the

distance between the score lines 42 and 43. The part 28 has its extensions 41 first bent upon the score lines 42 at a right angle and in the same directions as the sides 33 of the part 27. The portion of the extensions between the score lines 42 and 43 afford the sides and the front of the button and the extensions 41 outward of the score lines 43 form the rear or inner face of the front of the button, while the extension 45 after being bent on the score line 46 affords the top of the front of the button. It will thus be noted that the front of the button is in the nature of a hollow substantially rectangular element. Before the parts that constitute the front of the button are bent in a manner as heretofore described there is received in the pocket provided by the hollow front a plate that constitutes a slidable latch. The blank of this latch is best illustrated by Figure 16 of the drawings. 70 The slidable latch comprises a plate 49 of a comparatively less length than that of the pocket in the hollow front but is of a width approximately equaling that of the said pocket. The plate 49 is approximately centrally formed with a rectangular opening 50 but what I will term the upper wall provided by this opening has centrally projecting therefrom a tongue 51. The lower edge of the slidable latch plate 49 is formed with a central extension which is bent right-angularly to afford the same with a finger piece 52, of a width to be received in the longitudinal passage 39 of the T-hole slot in the front of the button. The plate that constitutes the body of the front and back of the button between the confronting edges of the bendable extensions 29 and 41 is rounded upon itself, as at 53, and this rounded portion affords a spring hinge between the back and front. The hinge has a tendency to force the back and front away from each other. 80

90 The shoulders 54 between the extensions 35 and 36 of the members 34 provide stop elements for limiting the swinging of the front in the direction of the back of the button. When thus brought together the notched or slotted portions 36 of the tongue carrying plates 34 are received through the transverse and widened passage 40 of the T-hole slot or opening and the slidable latch is moved downwardly in its pocket in the hollow front to bring its tongue 51 through the openings 37 and thereby effectively lock the front and back elements of the button in parallelism to 95 effectively hold a collar on a shirt band. 100

105 The construction and advantages of my 110 construction will, it is thought, be understood and appreciated so that further detailed description will not be required. Obviously I do not wish to be restricted to the precise detail herein set forth, the illustrative embodiment being designed merely to disclose two satisfactory designs of the improvement as 115 they now appear to me and, therefore, I hold 120

125 130

The construction and advantages of my construction will, it is thought, be understood and appreciated so that further detailed description will not be required. Obviously I do not wish to be restricted to the precise detail herein set forth, the illustrative embodiment being designed merely to disclose two satisfactory designs of the improvement as they now appear to me and, therefore, I hold

myself entitled to make such changes therefrom as fairly fall within the scope of what I claim.

Having described the invention, I claim:

- 5 1. A button or fastener for the purpose set forth, comprising two spaced members connected at one of their ends, a lip on one of the members designed to be received through the other member, and a slidable latch on the last mentioned member for engaging the lip.
- 10 2. A collar button or fastener of the type described, comprising two spaced plates connected at one of their ends and susceptible to spreading apart at the said connected ends, an outwardly extending lip on one of the members, the other member having a slot to receive the lip therethrough, and a finger operated slidable latch guided in the last mentioned member and engageable with the lip for fastening the members together.
- 15 3. A rear collar button or fastener, comprising a back plate and a front plate, which are spaced apart but which have their lower edges hingedly connected, said back plate having a rightangular extension providing a lip, said front plate having an opening therethrough for the passage of the lip and being also provided with a pocket in a line with said opening, a slidable latch guided in the pocket and movable to engage with the lip for latching the plates together, a button or fastener for connecting the rear of the collar to a shirt band, comprising a back plate and a front plate, each of which having parts there-
- 20 35 of bent to reinforce the same and the bent portions of the front plate providing the same with a pocket, the rear of the said front plate and the lower portion of the pocket being provided with openings, the rear plate having an extension providing a lip to be received through said openings, a slidable latch plate in the pocket having a lower finger hold and having a tongue to engage with the lip, and said front and back plates having their lower edges hingedly connected.
- 25 4. A fastener for the purpose set forth, comprising two connected plates movable toward or away from each other, a lip carried by one of the plates and a latch carried by the other plate to engage with the lip.
- 30 5. A button or fastener for the purpose set forth comprising two swingably connected plates, a lip carried by one of the plates, and a slidable latch carried by the other plate movable to engage with the lip.

In testimony whereof I affix my signature.

DANIEL NACHTIGAL.
